DESIGN FOR A TICKET PUNCH

Arthur R. Heise, Woodbridge, Conn., assignor to
The Wm. Schollhorn Company, New Haven,
Conn., a corporation

Application November 12, 1938, Serial No. 81,051

Term of patent 7 years

To all whom it may concern:

Be it known that I, Arthur R. Heise, a citizen of the United States, residing in Woodbridge, in the county of New Haven and State of Connecticut, have invented a new, original, and ornamental Design for a Ticket Punch, of which the following is a specification, reference being had to the accompanying drawing, forming part thereof.

I claim:

The ornamental design for a ticket punch, substantially as shown.

ARTHUR R. HEISE.
